UNITED STATES PATENT OFFICE.

HENRY DEMER, OF GREAT BEND, PENNSYLVANIA.

DESIGN FOR A GLASS VESSEL.

45,742.

Specification for Design.

Patented May 12, 1914.

Application filed January 26, 1914. Serial No. 814,595. Term of patent 3½ years.

To all whom it may concern:

Be it known that I, HENRY DEMER, a citizen of the United States, residing at Great Bend, in the county of Susquehanna and State of Pennsylvania, have invented a new, original, and ornamental Design for Glass Vessels, of which the following is a specification, reference being had to the accompanying drawings, forming a part thereof.

Figure 1 is a side view of a glass vessel embodying the new design; and, Fig. 2 is a plan view of the same.

The design, as illustrated in the drawings, is for a glass vessel having cut, or otherwise impressed therein a rose with stem and leaves as shown.

I claim:

The ornamental design for a glass vessel, as shown and described.

In testimony whereof, I have affixed my signature in the presence of two witnesses.

HENRY DEMER.

Witnesses:

PHILIP J. DEMER,
FRANK DEMER.
